UNITED STATES PATENT OFFICE.

ROBERT S. RAINS, OF VINEMONT, ALABAMA, ASSIGNOR OF ONE-HALF TO WILLIAM EARL JAMES, OF CULLMAN, ALABAMA.

AX.

1,282,001.

Specification of Letters Patent. Patented Oct. 15, 1918.

Application filed November 24, 1916. Serial No. 133,189.

To all whom it may concern:

Be it known that I, ROBERT S. RAINS, a citizen of the United States, residing at Vinemont, in the county of Cullman and State of Alabama, have invented certain new and useful Improvements in Axes; and I do hereby declare the following to be a full, clear, and exact description of the invention, such as will enable others skilled 5 in the art to which it appertains to make and use the same.

This invention relates to axes, and particularly to a sectional ax. It is an object of the present invention to provide an ax 15 of sectional form, the parts of which are adapted to be interlocked in assembled relation and are so designed that when assembled they will provide the ax eye for the handle, and it is a particular object of the 20 present invention to provide for a renewal, or substitution, or interchange of the parts of the ax so as to prolong its useful service. A further object of the invention is to provide a sectional ax having cutting wedges 25 or blade portions adapted to interlock with cheek plates, the latter being substantially duplicate and interchangeable, and further to provide an ax involving duplicate and interchangeable wedge or cutting blades, 30 and to provide for the positive securing, in assembled position, the sections of the ax.

With these and other objects in view the present invention consists of an ax comprising a plurality of sections having interlocking features and adapted to be securely fastened in assembled position upon a handle.

While I have shown my invention as embodied in the present instance in a double-bladed ax, it is to be understood that the principle of the invention may be carried into poll-axes, broad-axes, hand-axes, hammers, mattocks, picks, and various other tools and implements adapted to be mounted 40 upon wooden or other handles, and in the accompanying drawings illustrating this invention:

Figure 1 is a perspective view of the improved ax as applied to a handle.

50 Fig. 2 is a longitudinal central sectional view through the assembled ax, and

Fig. 3 is a perspective view of the separated parts of the ax.

In the form of the invention illustrated 55 the ax comprises substantially duplicate

wedge or cutting blades 2 having the usual cutting edges 3, and each of these blades has its thickened edge or portion 4 longitudinally grooved as at 5 and on opposite sides of the thickened end 4 the blade section is recessed or rabbeted as at 6 to form substantially circular seats for the central or intermediate sections 10 of the ax.

The sections 10 are shown as slightly concavo-convex in transverse section, and have at opposite sides substantially semi-circular lips or tongue portions 11, the outer surfaces of each of the intermediate sections or cheek plates 10 being adapted to conform nicely with the outer tapering surface of 70 the wedge or blade members 2 so that when the cheek plates 10 are assembled upon the wedge members 2, as shown in Figs. 1 and 2, the outer surfaces on the opposite sides of the ax proper form continuous, smooth 75 surfaces where the arcuate edges 12 of the cheek sections 10 register with the arcuate edges 7 of the recess or rabbets 6 in the respective wedge or blade members.

Each of the wedge or blade members 2 80 has its upper and thickened end provided with a longitudinal slot or groove 5, and these, in conjunction with the concaved surfaces 13 of the cheek plates 10 of the ax will, when the sections of the ax are assembled, form a handle receiving eye 14 into which the handle may be clamped.

For the purpose of securing the relatively detachable ax sections together suitable means may be provided, and in this instance 90 a simple form of fastening means is illustrated as comprising screws 15 having countersunk heads 16 to fit countersunk apertures 17 in the respective sides of the cheek plates and to enter a threaded portion 95 18 of the opposite cheek plate after passing through the interposed thickened end of the wedge or blade member 2. These screws serve to clamp the cheek plates firmly upon the interposed handle A and into the depressed or recessed seats 6 on opposite sides 100 of the blade sections.

One of the important features of the present invention consists of means for firmly interlocking the sections of the ax in assembled position so as to prevent relative movement of one on the other independently 105 of the fastening means or screws 15, and to that end each of the blade or wedge sections 2 is provided at its upper or thickened 110

end portion 4 with an aperture 20 of suitable outline, here shown as rectangular, and one of the tongue or lip members 11 of each cheek plate 10 is provided with a boss or 5 tenon portion 21 on its inner surface which is adapted to be inserted through its respective aperture 20 on the adjacent wedge or blade member 2. By making the tenon member 21 and the respective mortise aperture 20 of rectangular or other than circular 10 form, the wedge or cutter section is interlocked firmly with the complementary overlapping cheek members 10 so as to prevent relative shifting of one of these members 15 upon the wedge or blade portion 2.

While the planes of the bottom of the recesses 6 of each blade member 2 may be parallel, or substantially parallel, with each other, they are shown in Fig. 2 as being disposed slightly angularly to correspond approximately with the angle or taper of the side faces of the wedge 2 and the bowed outer surface of the overlapping cheek plates 10 when these latter are assembled upon a 20 wedge or blade member 2, and to secure a maximum length of thread area for the purchase or reception of the screws 15 I prefer that the screw threads for receiving them be formed in the lugs or tenons 21 as 25 shown at 18, Figs. 2 and 3.

From the foregoing it will be seen that I have provided a sectional ax comprising substantially duplicate and interchangeable side or cheek plates 10 adapted to be 30 clamped upon a handle and which are formed with interior opposed surfaces concaved sufficiently to form, when in assembled relation, an eye to receive the handle of the ax, and have provided a detachable 35 wedge or cutting blade or member 2 which may be interlocked by a mortise and tenon connection with the respective interlocking cheek plates 10, these latter having portions which are countersunk within seats formed 40 in the upper portion of the blade 2 so as to present substantially smooth exterior entering surfaces contiguous with the wedge surfaces on opposite sides of the ax. It is 45

Copies of this patent may be obtained for five cents each, by addressing the "Commissioner of Patents, Washington, D. C."

understood that while I have shown the invention as embodied in a double edged ax, 50 that the parts may be designed, constructed, and arranged as expedient in the erection of axes or tools of other types, so long as the members are formed of sections adapted to interlock with each other and capable of being securely fastened upon an inserted handle. 55

What is claimed as new is:

1. A sectional ax comprising a pair of 60 duplicate cutting blades each of which is thickest at its edge parallel to the cutting edge, said thicker edge being substantially straight, the sides of each bit recessed from 65 said thicker edge downwardly toward the cutting edge, each bit perforated transversely at its recessed area; and eye-forming side plates having parallel shoulders to abut the edges of assembled bits and reinforcing lips extending from the shoulders to fit flush 70 in the said recesses of said bits, the lips having apertures to receive fastening means passing also through the bits.

2. A sectional ax comprising a pair of 75 duplicate cutting blades each of which is thickest at its edge parallel to the cutting edge, said thicker edge being substantially straight and longitudinally grooved to fit the handle, the sides of each bit recessed from 80 said thicker edge downwardly toward the cutting edge, each bit perforated transversely at its recessed area; and eye-forming side plates having parallel shoulders to abut the edges of assembled bits and reinforcing lips extending from the shoulder to fit flush 85 in the side recesses of said bits, the lips having apertures to receive fastening means passing also through the bits, the walls of the grooved bit ends serving to take strains from the fastening means when the 90 handle is turned to pry with the ax.

In testimony whereof I affix my signature in presence of two witnesses.

ROBERT S. RAINS.
